United States Patent Office

Des. 186,180
Patented Sept. 22, 1959

186,180

WATCH

Jack Diamond, New York, N.Y., assignor to Helbros Watch Company, Inc., New York, N.Y., a corporation of New York

Application February 16, 1959, Serial No. 54,632

Term of patent 3½ years

(Cl. D42—8)

Fig. 1 is a top plan view of a watch, showing my new design.

Fig. 2 is a bottom plan view.

Fig. 3 is a side elevational view.

Fig. 4 is a side elevational view thereof partly in section.

I claim:

The ornamental design for a watch, substantially as shown.
